UNITED STATES PATENT OFFICE.

FLOYD B. STOBER, OF BYERS, COLORADO.

TWINE-CUTTER.

1,063,896.

Specification of Letters Patent.

Patented June 3, 1913.

Application filed August 23, 1912. Serial No. 716,741.

To all whom it may concern:

Be it known that I, FLOYD B. STOBER, a citizen of the United States, residing at Byers, in the county of Arapahoe and State 5 of Colorado, have invented new and useful Improvements in Twine-Cutters, of which the following is a specification.

An object of the invention is to provide a device for cutting twine.

10 The invention embodies, among other features, a device preferably mounted on the fingers of the hand and arranged to lie within the palm of the hand so that an end of the twine which has been previously 15 passed around a package to secure the wrapper thereof, when engaged with the device, will be severed thereby, the device being so arranged that the same will not interfere with the manipulation of the fingers of the 20 hand in tying and securing the package.

The invention further embodies a device that can be cheaply and efficiently constructed and in which the various parts thereof are 25 preferably struck from single sheets of material, thus presenting a device made almost entirely from stamped metal.

In the further disclosure of the invention reference is to be had to the accompanying drawings, constituting a part of this specification, 30 in which similar characters of reference denote corresponding parts in all the views, and in which:

Figure 1 is a perspective view of the device showing the same in applied position 35 for severing a piece of twine bound around a package, the package, twine and the hand upon which the device is mounted being shown in dotted lines; Fig. 2 is a vertical longitudinal sectional view of the article; 40 Fig. 3 is a vertical transverse sectional view; Fig. 4 is a view of the blank adapted to form the holder; Fig. 5 is a view of the blank adapted to form the blade holder or casing; Fig. 6 is a perspective view of the 45 blade; and Fig. 7 is a side elevation of the pin for pivoting the blade on the holder.

Referring to the views and more particularly to Fig. 4, use is made of a holder body 10, preferably formed of a blank 11, provided 50 with extensions 12 which, when bent, will form finger grips 13 as shown in Fig. 1, the free ends of the extensions being adapted to engage the under side of the holder body and 55 preferably made of a bendable material so that the finger grips can be enlarged or

restricted to conveniently fit the fingers of the operator.

The main portion of the blank 11 is bent upon itself to form a casing 14, an extension 15 of the blank being provided to form an 60 edge 16 of the casing and an extension 17 of the blank being adapted, when bent, to form a securing member 18 for a flat spring 19, mounted within the casing 14, for a purpose that will be hereinafter more fully disclosed. 65 The inner ends of the finger grips 13 are preferably enlarged to form guard plates 20, the said guard plates being slightly curved in order that the finger grips 13 can be conveniently adjusted to the fingers of 70 the hand, the mentioned guard plates being clearly shown in Fig. 1 and in the blank in Fig. 4.

A blade holder 21 is preferably made of a blank 22, shown in Fig. 5, the mentioned 75 blank being bent upon itself so that ears 23 of the blank will form a head 24 for arranging a blade 25 in the blade holder 21, the blank 22 being provided with extensions 26, which, when the blank is bent upon itself, 80 will form securing members 27 for securing an end of the blade to the blade holder. An end of the blank terminates in an enlarged portion 28 which, when the blank 22 is bent to form the blade holder 21, will be rounded 85 on the under side and bent slightly upward to form a guide plate 29. The blade 25 has a plurality of opposite cutting edges 30 and is provided at each end thereof with a notch 31. Now when the blade 25 is mounted in 90 the blade holder 21, a pin 32 is arranged to extend transversely through the head 24 of the blade holder and through one of the notches 31, thus rigidly securing one end of the blade 25 within the blade holder, while 95 at the same time, in view of the particular manner in which the pin 32 is mounted, the blade holder will swing on the pin 32, the other end of the blade 25 being retained in engagement with the blade holder by the 100 securing members 27 which have been bent to engage the under side of the blade and secure the same in the blade holder. The flat spring 19, mentioned heretofore, when mounted in the casing 14 as shown in Fig. 105 2, will have an end thereof secured to the casing by the member 18 and the free end of the spring engages the head 24 of the blade holder 21 to normally exert a downward pressure on the blade holder and retain the 110

same within the casing 14. The pin 32 is provided with a laterally extending shank 33 terminating in a hook 34 adapted to be received in notches 35, preferably as shown in the blank 11 in Fig. 4, the mentioned hook 34, when mounted in the notch, being adapted to secure the pin 32 to the casing 14 as will be readily understood. It will now be seen that the blade 25 can be readily reversed in the blade holder 21 when the protruding cutting edge thereof becomes worn or dull, it being seen that when the blade is reversed in the blade holder the other cutting edge will protrude and the other notch 31 of the blade will have the pin passing therethrough, thus positively securing the blade within the blade holder.

In the use of the device, the cutter is placed on the fingers by passing the fingers through the grips 13, the grips being adjustable relatively to the fingers as mentioned heretofore and, as shown in Fig. 1, when the device is mounted on the hand in the manner mentioned, the same will lie in the palm of the hand and will not interfere with the fingers of the hand so that the fingers can be employed to tie the package with twine, as shown. Now when it is desired to sever that portion of the twine adjacent the usual knot that secures the twine to the package, the mentioned portion of the twine is passed beneath the guide plate 29, thus exerting an upward pressure on the blade holder 21 and operating the same against the action of the spring 19 so that when the portion of the twine passes over the guard plates 20, the twine will engage the cutting edge of the blade 25, which, exerting a downward pressure through the medium of the spring 19, will sever the twine, and the action of the spring 19 will then return the blade holder and blade within the casing 14, it being readily seen that the guide plate 29 aids in guiding the twine to cutting position, an edge of the blade holder 21, adjacent the guide plate 29, being inclined downwardly toward the blade to materially aid in moving the twine into cutting position.

As mentioned heretofore, the casing 14 is preferably made of a single piece of stamped metal and the blade holder 21 is also stamped from an integral piece of material, thus providing a device that can be cheaply and efficiently constructed and which, when mounted on the hand, will not

interfere with the proper manipulation of the fingers in tying the package.

Referring to Fig. 4 it will be seen that a plate 36 is formed with the blank 11, adjacent the extension 17, and the mentioned plate is provided with a notch 37 so that when the plate is bent into the position shown in Fig. 2, the free end of the blade holder 21 will seat in the notch 37, thus limiting the downward movement of the blade holder in the casing.

Having thus described my invention, I claim:

1. A twine cutter comprising a casing formed of an integral piece of material, finger grips formed on the said casing, guard plates formed on the casing adjacent the inner ends of the finger grips, a blade holder formed of a single piece of material and mounted to swing in the said casing, a blade mounted on the blade holder, a guide plate formed on the free end of the blade holder, and a spring secured to the said casing and engaging the said blade holder to normally retain the said blade within the casing.

2. A twine cutter comprising a casing, means formed on the said casing for securing the same to the hand, a blade holder mounted to swing on the casing, a spring secured in the said casing and engaging the said blade holder to normally retain the same within the casing, a blade mounted on the said blade holder, and a guide plate formed on the free end of the blade holder.

3. A twine cutter comprising a casing formed of a single piece of material, finger grips on the said casing, guard plates on the casing adjacent the ends of the finger grips, a blade holder formed of a single piece of material and mounted to swing in the said casing, a blade carried by the blade holder, a guide plate on the free end of the blade holder, a spring secured to the casing and engaging the blade holder to normally retain the blade within the casing, and a notched plate formed with the piece of material forming the casing and adapted to constitute a seat for the free end of the blade holder.

In testimony whereof I affix my signature in presence of two witnesses.

FLOYD B. STOBER.
